UNITED STATES PATENT OFFICE

1,963,372

FOLDING BED

William A. Moeller, Los Angeles, Calif.

Application December 19, 1931, Serial No. 582,055

3 Claims. (Cl. 5—337)

This invention relates to a folding bed and relates more particularly to a davenport type of folding bed that may be used as a sofa or davenport when in the folded position and that may be used as a bed when extended.

It is a general object of the present invention to provide an improved davenport type of folding bed that occupies a minimum amount of space and has the appearance of a typical davenport when in the normal folded condition and that forms a particularly effective and comfortable bed when in the extended position.

An important object of the invention is to provide a sofa or davenport type of folding bed in which the bed frames may be of any standard length and which has an extensible support or head-rest at the head of the bed frames for carrying pillows or the like.

Another object of the invention is to provide a folding bed construction of the character mentioned in which the sleeping person's head lies in an entirely open area on the head-rest and is not back of the upwardly projecting back structure of the davenport.

Another object of the invention is to provide a folding bed construction of the character mentioned in which an arm or end of the davenport proper is foldable to a down or substantially horizontal position when the bed frames are extended to provide a large, convenient bed and to provide for the use of the extensible head-rest or pillow support mentioned above.

Another object of the invention is to provide a folding bed of the character mentioned that is particularly simple and easy to operate between the folded or normal position and the extensible position, where the davenport arm is down and the pillow support is extended at the head end of the bed frames.

Another object of the invention is to provide a bed structure of the character mentioned in which the folding bed mechanism is entirely concealed when the parts are in the normal folded positions, so that the structure cannot be distinguished from a typical or usual davenport.

A further object of the invention is to provide a folding bed construction of the character mentioned that is simple and inexpensive of manufacture and that may be embodied in sofas or daventports of various classes and styles.

Other objects and features of the invention will be best and more fully understood from the following detailed description of typical preferred forms and applications of the invention,

throughout which description reference is had to the accompanying drawings, in which:

Fig. 1 is a perspective view of a sofa or davenport embodying the features of the present invention. Fig. 2 is a front elevation of one end portion of the structure with the cushions removed and illustrating the end in the down or collapsed position. Fig. 3 is an enlarged vertical detailed sectional view taken substantially as indicated by line 3—3 of Fig. 2. Fig. 4 is a top or plan view showing the bed frames and the end in the extended positions. Fig. 5 is a view similar to Fig. 4 illustrating the head-rest or support in the extended position. Fig. 6 is a front elevation of an end portion of the structure being a view taken as indicated by line 6—6 on Fig. 5. Fig. 7 is an enlarged detailed view of the mechanism for operating the shiftable end. Fig. 8 is an enlarged detailed sectional view taken substantially as indicated by line 8—8 on Fig. 4. Fig. 9 is an enlarged elevation of one of the support means being a view taken as indicated by line 9—9 on Fig. 4. Fig. 10 is a side elevation taken as indicated by line 10—10 on Fig. 9, and Fig. 11 is an enlarged vertical detailed sectional view taken as indicated by line 11—11 on Fig. 5.

The folding bed construction provided by the present invention is adapted to be embodied in davenport or sofa constructions of various styles and forms. Throughout the following detailed disclosure, the invention will be described as embodied in a more or less typical type of davenport, it being understood that the invention is not to be taken as limited or restricted to the specific form or application about to be described, but that it is to be taken as including any features or modifications that may fall within the scope of the claims.

The sofa or davenport illustrated in the drawings includes generally, a frame comprising a base or seat portion 10, a back 11, and ends 12 and 13. The base 10 is an elongated, rectangular structure for carrying the springs and cushions and includes a front runner or member 14 and a rear member 15. The back 11, the ends 12 and 13 and the frame member 14, may be suitably upholstered in the usual manner. The base 10 is provided with spaced feet 16 and removable cushions 17 are arranged in the device when its parts are in the normal or folded positions. The davenport includes various other parts and features common to structures of this general character.

The folding bed construction provided by the present invention includes generally, two bed frames 18 and 19, means 20 mounting the bed

frames 18 and 19 on the base 10 so that they are operable between positions one above the other in the base 10 and positions in the same horizontal plane where the frame 18 is at the front of the base, means 21 whereby the end 13 is operable between the normal vertical position and a down or extended position, and a head-rest or pillow support 22 operable between a folded position between the two folded bed frames 18 and 19 10 and an extended position at the ends of the bed frames.

The bed frame 18 is the outer bed frame and forms the seat frame of the structure when the parts are in the folded or collapsed positions. 15 The bed frame 18 is a rectangular structure and may be formed of angle iron or the like. A suitable spring structure 22 is carried by the frame 18. The bed frame 18 is supported above the base 10 when the parts are in the folded positions 20 and its top and front may be covered with upholstery 23. One or more legs 24 project downwardly from the bed frame 18 to engage the member 14 and support the bed frame on the base when in the in or normal position.

25 The bed frame 19 which is the inner frame is similar generally to the frame 18, that is, it is formed of angle iron or the like, and carries the usual spring structure 25. The inner bed frame 19 is disposed below the frame 18 when the parts 30 are in their collapsed positions, and is operable vertically upon the outer frame 18 being shifted between the folded and extended positions.

The means or mechanism for mounting the bed frames 18 and 19 on the base 10 may be varied 35 considerably without departing from the broader principles of the invention. In the drawings I have illustrated an extensible mounting means 20 similar generally to the corresponding structure described and claimed in my co-pending application entitled *Folding bed* Serial No. 357,594, filed April 23, 1929. The means 20 is such that the outer bed frame 18 is operable upwardly from the normal position, then horizontally forward, and then downwardly to a position at the forward end of the base 19. During shifting of the outer bed frame 18 to the out position, the inner frame 19 moves upwardly to a position in the same horizontal plane to which the outer bed frame 18 is operated.

50 The means 20 includes like mechanism at the opposite ends of the frames 18 and 19. I will proceed with a detailed description of the mechanism 20 at one end of the bed structure, it being understood that such description applies to the 55 mounting means 20 at both ends of the bed frames. The means 20 includes a horizontal mounting member 26 stationarily attached to the base 10 adjacent the end 13. Two like links 27 are provided to connect the outer frame 18 with the mounting member 26. The links 27 have their upper ends pivotally connected to an end of the outer frame 18 and have their lower ends pivotally attached to the mounting member 26. The links 27 are related and proportioned so that the bed frame 18 is operable upwardly, then outwardly and then downwardly from the position illustrated in Fig. 3 of the drawings to the position illustrated in Figs. 4, 5 and 6 of the drawings. Means is provided for supporting the outer bed frame 18 when in the extended or out position. A leg 28 has its upper end pivoted to the end of the frame 18 at a point adjacent its forward end. An operating rod 29 operatively connects the leg 28 with one of the links 27 so that 75 the leg 28 is automatically shifted from a posi-

tion at the end of the frame 18 to a vertical position projecting downwardly from the bed frame when the bed frame is operated to the out position. The rod 29 is pivotally attached to an extension 27a on one of the links 27 and its outer end is pivotally connected with the leg 28.

An arm 30 is rigidly attached to each link 27 and is slidably and pivotally connected with the inner bed frame 19. The arms 30 carrying the inner bed frame 19 for vertical movement during shifting of the outer bed frame 18 between the in and out position. Pins 31 on lower ends of the arms 30 cooperate with slots 32 in the inner bed frame 19 to pivotally and slidably connect the arms with the inner bed frame. A control link 33 is pivotally connected with the inner bed frame 19 and one of the links 27 to control the movement of the inner bed frame 19 and to maintain the arms 30 in parallelism at all times. A spring counter balancing means 34 is provided to facilitate the easy operation of the bed frames 18 and 19.

The means 21 provides for the shifting of the end 13 from the normal vertical position to a down position such as is illustrated in Figs. 2, 5 and 6 of the drawings. The means 21 includes a hinge or pivotal connection between the end 13 and the base 19. In the particular case illustrated in the drawings, hinges 35 connect the lower end of the arm or end part 13 with the base 10. Means is provided for manually operating the end 13 between the normal up position and the down or extended position. An operating rod 36 extends partially across the back 11 at a point below the upholstery. A bracket 37 projects from the inner side of the end part 13, and a link 38 operatively connects the rod 36 with the bracket 37. The link 38 is pivotally connected with the bracket 37 and the rod 36. The axis of the pivotal connection between the link 38 and the rod 36 is vertical so that the rod 36 may have limited oscillatory movement in a horizontal plane. In the preferred form of the invention, means is provided for limiting the downward movement of the end part 13 so that the part 13 is held in a position above and free of the floor when extended. A vertical stop 39 is provided on the base or back 11 at a point adjacent the end of the operating rod 36. The link 38 is bent or shaped to have a vertical shoulder 40 adapted to cooperate with the stop 39 to limit the downward movement of the arm part or end 13.

Toggle or lever means is provided for operating the rod 36. A lever 41 is pivoted to a stationary frame member 42 on the back 11. A pivot pin 43 connects the rod 36 with the lever 41 at a point intermediate the ends of the lever. A suitable tape or pull 44 may be provided on the outer end of the lever 41. The rod 36, the lever 41, and the various other parts of the means 21 are located so as to be normally covered and concealed by the removable cushions 17 when the parts are in the normal or unactuated positions. When the end 13 is in the normal vertical position, the lever 41 projects from its pivot point toward the stationary end 12. To lower the end 13 the lever 41 is pulled forwardly so that it throws over center to the position illustrated in Fig. 7 of the drawings. It will be apparent how the end 13 may be easily and quickly operated between the up and down positions by simply pivoting or throwing over the lever 41. It is to be noted that the lever 41 is arranged so that the end 13 cannot be accidentally thrown or shifted to the

down position as the lever 41 must be thrown over center to operate the end 13.

The pillow support or head-rest 22 is provided to project from or extend from the ends of the bed frames 18 and 19 when the bed frames are in their extended positions and the end 13 is in the down position. The head-rest 22 is operable between the folded position in the base 10 and an extended position at the head ends of the bed frames 18 and 19. In accordance with the invention the support or head-rest 22 includes a rectangular frame 50 and a body of fabric 51 carried by the frame 50. The frame 50 may be a simple structure formed of angle iron or the like, and the fabric 57 is stretched or drawn across the frame 50. The margin or edge portions of the fabric 51 are yieldingly or flexibly attached to the frame 50. A plurality of spaced helical or spiral springs 52 extend between the frame 50 and the edge portions of the fabric 51 to yieldingly attach the fabric to the frame.

When the bed frames 18 and 19 are in their in or folded positions, the head rest 22 is disposed between them with its greatest length longitudinally of the bed structure. The head rest 22 is carried by the inner bed frame 19 and is operable to the extended or out position after the bed frames 18 and 19 have been shifted to their out positions. An arm 53 projects laterally from one corner of the frame 50 and is swivelly connected with the inner bed frame 19. A bracket 54 projects upwardly from the inner bed frame 19 and an angle member 55 is mounted on the upper end of the bracket to pivot about a vertical axis. A horizontal pivot pin 56 connects the outer end of the arm 53 with the angle member 55. With the swivel mounting just described, the head rest 22 may be readily operated between the positions illustrated in Figs. 4 and 5 of the drawings. The invention provides an improved means for holding or supporting the head rest 22 in the extended position. A rest or stop 57 projects upwardly from the inner bed frame 19 at a point adjacent the bracket 55. The frame 50 of the head-rest is adapted to engage the upper end of the stop 57 when the head-rest is in the out or extended position. The upper end of the rest or stop 57 is inclined to have point or line contact with the frame 50.

The outer end of the frame 50 is supported on the outer bed frame 18 when the parts are in the out positions illustrated in Fig. 5. An arm 58 projects laterally from an outer corner of the frame 50 and is adapted to cooperate with a disappearing or collapsible support 59 on the bed frame 18. The support 59 normally lies adjacent the end of the bed frame 18 when the parts are in their folded position as illustrated in Fig. 3 and is operable to a vertical position where it projects upwardly from the frame 18 when the parts are in their out positions. The lower end of the support 59 is pivotally connected with the bed frame 18 by the pivot pin 60 which connects the leg 28 to the bed frame. A link 61 is pivotally connected to the member 29 and the support 59. The link 61 operates the support 50 to the vertical position during shifting of the outer bed frame 18 to the out position. An inwardly projecting head 62 is provided on the upper end of the support 59. A slot 63 is provided in the upper end part of the support 59 and extends into the head 62. When the head rest 22 is swung to the out position, the arm 58 is moved past the rest 59. After the head rest 22 has been swung to an extreme out position it is

slightly tilted and swung back so that the arm 58 is passed through the slot 63. The cooperation of the arm 58 with the slot 63 supports the outer end of the head rest 22 on the bed frame 19 and holds the head rest 22 against undesirable looseness and movement. The supports 57 and 59 carry the opposite ends of the head rest 22 so that the head rest is effectively supported on the bed frames and is properly steadied. The supports 57 and 59 are proportioned and related so that they hold the head rests 22 in a tilted position where it is inclined downwardly and inwardly toward the bed frames 18 and 19.

It is believed that the utility and practicability of the bed construction provided by the present invention will be readily apparent from the foregoing detailed description.

When the parts are in their normal positions illustrated in Fig. 1 of the drawings, the bed frames 18 and 19, the means 20 and 21 and the head-rest 22 are entirely concealed. When it is desired to open out the construction to the extended position, the cushions 17 may be removed and the end 13 lowered by pulling the lever 41 forwardly to throw over center. The bed frames 18 and 19 may then be extended to the positions illustrated in Figs. 4 and 5 of the drawings. During operation of the bed frames to the extended positions, the support 59 is automatically moved to the vertical position where it projects upwardly from the frame 18. The head rest 22 may be easily swung to the out position and the arm 58 passed through the slot 63. It is to be noted that the support 59 is vertical when carrying the head rest 22 so that the load is in direct alignment with the pin 60 and the support does not have any tendency to turn or collapse. When the end 13 is in the down position the bed frames 18 and 19 are readily accessible and the construction provides ample head room. The head rest 22 adds materially to the length of the bed structure and permits the application of the folding bed to a comparatively short davenport or sofa. The folding bed construction described above may be easily embodied in typical sofa or davenport forms with very little modification and does not affect the normal outward appearance of the structure.

Having described only a typical preferred form of my invention, I do not wish to limit myself to the specific details set forth, but wish to reserve to myself any changes or variations that may appear to those skilled in the art or fall within the scope of the following claims:

Having described my invention, I claim:

1. A folding bed including a base, two bed frames, means mounting the bed frames on the base for movement between positions one above the other and positions adjacent one another in the same horizontal plane, a head-rest, means mounting the head-rest for movement between a position between the bed frames and a position at the ends of the bed frames, and a foldable support on the outermost bed frame automatically projected to a position to be engaged by a part on the head-rest upon extension of the bed frames.

2. In a folding bed, a base, an outer bed frame, means mounting the outer bed frame on the base for movement between a position above the base and a position forward of the base, an inner bed frame normally spaced under the outer bed frame in the base, means for operating the inner bed frame vertically to a position adjacent the outer bed frame, a head-rest carried by the inner bed frame operable between a normal substan-

tially horizontal position above the inner bed frame and an inclined position at an end of the assembly of the two frames, a normally collapsed foldable support on the outer bed frame, and means automatically projecting the support to a position for engagement by the head-rest when the outer bed frame is moved to its position forward of the base.

3. In a folding bed, a base, an outer bed frame, 10 means mounting the inner bed frame on the base for movement between a position above the base and a position forward of the base, an inner bed frame normally spaced under the outer bed frame in the base, means for operating the inner

15

bed frame vertically to a position adjacent the outer bed frame, a head-rest carried by the inner frame operable between a position above the inner frame to a position at an end of the assembly of the two bed frames, and means for supporting the head-rest on the outer bed frame when in the extended position, the last mentioned means including, a support on the outer bed frame normally substantially horizontal, means for automatically operating the support to a vertical position upon operation of the outer bed frame to the extended position, and an arm on the head-rest for cooperating with the support.
